MAX PAUL ERNST HOHN, OF DRESDEN, GERMANY, ASSIGNOR TO THE FIRM UNI-
VERSELLE CIGARETTENMASCHINENFABRIK J. C. MULLER & CO., OF DRESDEN,
GERMANY

MEANS FOR COUNTER ROLLING A CIGARETTE PAPER

Application filed November 17, 1927, Serial No. 238,937, and in Germany November 26, 1926.

Cigarette shells or paper cases with mouth-pieces are formed in well known manner by inserting into the cigarette shell from one end a so-called mouth-piece spiral. Such spirals before being inserted in the shell are coiled to small diameter and after being inserted and released tend to expand. As the spirals are formed of a spirally coiled stiff paper strip the outer coil of the spiral does not lie closely against the cigarette paper shell. To obtain close adhesion of the outer coil of the spiral to the shell a so-called counter-rolling device has been employed in which the shell is introduced into the gap between a stationary counter-rolling surface and a rotating roller or the like in such manner that in such gap or channel the shell is frictionally rotated, such rotation producing further opening of the mouth-piece spiral and ensuring close adhesion of the outermost coil of the mouth-piece spiral to the wall of the shell.

Experience has shown that the desired result is not always satisfactorily obtained by means of such known counter-rolling devices. The shell during its passage between the counter-rolling surface and the roller or the like is as it were neglected and some shells are more counter-rolled than others and some of the shells pass through the counter-rolling device without having been subjected to the required treatment.

By mounting the cigarette shell in accordance with this invention on a freely rotatable roller and rolling such roller over a counter-rolling surface then (assuming the correct selection of the feed movement of the roller and that the direction of rotation is correct) the shell must of necessity be subjected to the rolling movement and the spreading of the mouth-piece spiral must be effected.

Under this method each separate shell is subjected to a counter-rolling operation with certainty; the shell is positively held in the correct position and it is smoothly guided through the counter-rolling device without danger of displacement and consequent damage to the shell.

My new method may be performed by means of a device in which the cigarette shells

are disposed in pockets on the periphery of a rotating drum having associated therewith a plunger for each pocket, each plunger being provided at one end with a freely rotatable roller, the plungers being adapted to rotate in connection with the drum and their rollers arranged to roll over a counter rolling surface, disposed around the drum, during certain periods of the rotation of said drum.

The device is arranged to permit delivery of the finished counter rolled shells to an endless belt or the like directly from the drum without the need for any specially controlled grippers or the like.

The accompanying drawings illustrate the invention by way of example. In these drawings Figs. 1 and 2 show a vertical longitudinal section and a plan view respectively of the new device in conjunction with a counter-rolling device of known form. Fig. 3 shows another modification of the arrangement of the new counter-rolling device in side elevation or vertical transverse section.

Referring to the embodiment illustrated in Figs. 1 and 2 the cigarette shells 1 provided at one end with an inserted mouth-piece spiral and delivered from the cigarette-shell making machine (not shown) are fed by means of a gripper 2 through a channel or passage 3 to said device. The gripper 2 consists of a rake, the tines of which project from beneath through longitudinal slots in the walls of the channel and are located behind the cigarette shells 1. The rake is carried by a support 4 which is mounted on the crank pin 5 of a crank 6. The rod shaped end 7 of the support is longitudinally movable in a guide which is adapted to rock about a transverse pivot 9. The rake 2 is thus upon rotation of crank 6 in direction of the arrow given such a movement that the ends of its tines describe the closed curve shown by a dotted line in Fig. 1. In consequence the tines push the shells 1 forward in the channel 3 and deliver them finally to the counter-rolling channel 10. Such counter-rolling channel is formed in known-manner by a rotating roller 11 and a curved counter-rolling surface 12 concentric therewith and suitably spaced therefrom. The shell 1 is guided

through the gap between the periphery of the roller 11 and the counter-rolling surface 12 and is thus counter-rolled in known manner.

In accordance with the present invention the shell 1 leaving the counter-rolling channel 10 is delivered to the upper flight of an endless feed band 13 which is guided over the pulleys 14 and 15 and moves in the direction of the arrow. The shells pass from the feed band 13 over a bridge member 16 to a drum 17 which is provided on its periphery with pockets 18 each serving to receive a cigarette shell. Drum 17 rotates on a drum shaft 19 in the direction of the arrow and takes with it the cigarette shells delivered thereto so that a cigarette shell 1 lies in each pocket 18. On the drum shaft 19 is secured a disc 20 which is provided with a series of axial orifices of rectangular form disposed concentrically of the drum shaft. In these orifices are guided shafts 21 which carry at their ends rollers 22 and which are provided at their opposite ends with reduced portions 23 of circular cross sections. On these reduced portions are mounted freely rotatable rolls 24. Around the portions of the shafts 21 on the same side of disk 20 as the rollers 22 and between said rollers and said disk are mounted coiled springs 25 which tend to press the shafts with the rollers 22 against a stationary cam disc 26 which is secured to a stationary bearing 27.

The support 20 for the shafts 21 rotates with the drum 17 and the stationary cam disc 26 causes the shafts with the ends carrying the rolls gradually to enter the pockets 18 on the drum 17 and to enter the cigarette shells located in such pockets. The device is naturally so disposed that the rolls 24 enter the mouth-piece ends of the shells, the rolls being of a length corresponding to the length of the mouth-piece spirals.

Around the drum is mounted a counter-rolling surface, for instance a casing 28, which partly embraces the drum, the distance of the casing from the drum being such that the rolls 24 taking part in the rotation of the drum come in contact with the inner wall of the casing and roll around it. The mouth-piece ends of the cigarette shells fitted over the rolls are thus counter-rolled and the outer coils of the mouth-piece spirals are pressed against the walls of the shells.

On further rotation of the drum, shafts 21 are gradually retracted and the rolls 24 withdrawn from the cigarette shells and finally are completely withdrawn when the shells reach the lowermost part of the drum 17. The counter-rolling surface terminates at this point and the finished counter-rolled cigarette shells pass on to the feed band 29 and can be directly delivered therefrom. The surface 30 provided above the feed band prevents any shells from being thrown to the right-hand

over the feed band 29 when the drum is rapidly rotated.

In the embodiment shown in Fig. 3, the plungers 21 are provided with rolls 24 and a counter-rolling surface 28 is provided as in the arrangement shown in Figs. 1 and 2. In this instance however, the shells 1 are led direct to the pockets 18 of the drum through the channel 3 by means of a rake-like implement 2.

In order that the rolls 24 may gradually come into engagement with the counter-rolling surface 28 either this counter-rolling surface is not exactly concentric with the drum shaft 19 as it is in Fig. 1 or else the orifices for the shafts 21 are not arranged concentrically of the disc.

In performing the new method it is immaterial whether the rolls on which the shells with their mouth-piece ends are pushed are rolled around a counter-rolling surface or whether the roll carrier is stationary and the counter-rolling surface is moved around the rolls.

I claim.

1. Means for counter-rolling cigarette shells comprising in combination a rotatable drum, said drum formed with peripheral pockets each adapted to receive a cigarette shell, plungers, one for each pocket of said drum, said plungers, rotatable with said drum, rollers one mounted on each of said plungers said rollers freely rotatable on said plungers and adapted to enter the mouth-piece ends of said cigarette shells and a counter-rolling surface embracing said drum.

2. Means for counter-rolling cigarette shells having an inserted mouth-piece spiral comprising in combination a roller, a counter-rolling surface associated with said roller and providing with said roller a passage for the cigarette shells to be counter-rolled, a feed band associated with said counter-rolling surface, a rotatable drum disposed at the end of said feed band remote from said counter-rolling surface, a bridge member located between said drum and said feed band, said drum formed with peripheral pockets, each adapted to receive a cigarette shell, plungers one for each pocket of said drum, said plungers rotatable with said drum, rollers one mounted on each of said plungers, said rollers freely rotatable on said plungers and adapted to enter the mouth-piece ends of said cigarette shells and a counter-rolling surface embracing said drum and co-operating with said rollers and cigarette shells.

3. Means for counter rolling a cigarette paper shell having an inserted mouthpiece spiral, comprising a pocket member adapted to receive a cigarette shell, spreading means associated with said pocket member and including means adapted to be inserted into the mouthpiece spirals in said shells, and external means cooperating with said last

named means to produce a counter rolling effect.

4. Means for counter rolling a cigarette paper shell having an inserted mouthpiece spiral, comprising a rotatable pocketed drum adapted to receive cigarette shells, spreading means associated with said drum, including plungers to be inserted into the mouthpiece spirals of said shells, and external means cooperating with said last named means to produce a counter rolling effect.

5. Means for counter rolling a cigarette paper shell having an inserted mouthpiece spiral, comprising a rotatable drum formed with peripheral pockets each adapted to receive a cigarette shell, spreading means mounted adjacent to said drum, including plungers rotatable with said drum, rollers mounted on each of said plungers, said rollers adapted to enter the mouthpiece ends of said cigarette shells, and a counter rolling surface embracing said drum and cooperating with said rollers to produce a counter rolling effect.

25 6. Means for counter rolling cigarette shells having inserted mouthpiece spirals, comprising in combination, a roller, a counter rolling surface associated with said roller and providing with said roller a passage for the cigarette shells to be counter rolled, feeding means associated with said counter rolling surface, a pocket member at the end of said feeding means remote from said counter rolling surface, a bridge member located 30 between said feeding means and said pocket member, spreading means associated with said pocket member including means adapted to be inserted into the mouthpiece spirals in said shells, and external means cooperating with said last named means to produce a counter rolling effect.

7. Means for counter rolling cigarette shells having inserted mouthpiece spirals, comprising in combination, a roller, a counter 45 rolling surface associated with said roller and providing with said roller a passage for the cigarette shells to be counter rolled, feeding means associated with said counter rolling surface, a rotatable drum at the end 50 of said feeding means, remote from said counter rolling surface, formed with sockets each adapted to receive a cigarette shell, spreading means associated with said drum, including plungers to be inserted into the 55 mouthpiece spirals of said shells and external means cooperating with said spreading means to produce a counter rolling effect.

In testimony whereof I affix my signature.

60 MAX PAUL ERNST HOHN.
